G. BRYAR

STRAP WRENCH

Original Filed Dec. 15, 1921

Inventor,
George Bryar;
By
A. B. Myhann,
Attorney.

UNITED STATES PATENT OFFICE.

GEORGE BRYAR, OF BOSTON, MASSACHUSETTS, ASSIGNOR OF THREE-FOURTHS TO EDWIN W. FORD AND ONE-FOURTH TO JAMES C. FLANNERY, BOTH OF BOSTON, MASSACHUSETTS.

STRAP WRENCH.

Application filed December 15, 1921, Serial No. 522,454. Renewed March 21, 1924.

To all whom it may concern:

Be it known that I, GEORGE BRYAR, a citizen of the United States, residing at Boston, in the county of Suffolk and State 5 of Massachusetts, have invented certain new and useful Improvements in Strap Wrenches, of which the following is a specification.

The object of this invention is the construction of a wrench for screwing up piping having finished surfaces, either brass or plated, which shall be capable of adjustment to such piping, which will not slip but will tightly grip the same, and at the same 10 time will not injure the surfaces to which it is applied.

To this end I provide a handle having a head to which an end of the strap is permanently attached, and a shank along which 15 the other end of the strap can be adjustably secured, my preferable means for such adjustment consisting in threading the shank and mounting thereon an internally threaded collar to which the end of the strap is 20 attached. I also provide means for keeping the threaded collar from turning on the shank relative to the head, in order to maintain the head and collar always in proper 25 relationship. I further improve the wrench 30 by forming its head with a rounded nose by means of which the strap is made to enclose nearly the entire periphery of the piping being acted upon, and thereby to ensure a more perfect grip thereon.

The drawing forming part of this specification is a side view of a pipe wrench embodying my improvements, the piping being shown in section.

The handle 1 has rigidly projecting 35 therefrom a shank 2 threaded for practically its entire length, and having a head 3 rotatably mounted upon its outer end. From this head projects a lip 6 rounded at its end and having its surface 7 slightly inclined 40 relative to the shank. Upon this surface is fastened an end of a strap 9 by any suitable attaching device, as a screw 10, the strap itself being preferably of ribbon steel.

Mounted on the shank 2 and internally 45 threaded to coat therewith, is a collar 11 having a finger 12 projecting therefrom, the edge of this finger being serrated, as at 13.

The collar 11 and the head 3 are made to turn on the shank 2 in unison by a slender rod 14 rigid with one thereof but slideable in an eye 15 of the other member. Thus arranged, when the shank is revolved it turns equally in both the head and collar. 55

The end of the strap 9 not attached to the head 3 is provided with a slotted plate 16 60 adapted to be engaged with the serrations of the finger 12, either close to the collar or farther therefrom, as the best action of the wrench demands.

In using this wrench, the plate 16 is removed from its engagement with the finger 12 to permit the strap 9 to be passed about the piping to be turned. Then the handle 1 is rotated until the collar 11 is 65 propelled thereby to a point at which the finger 12 readily engages the slotted plate 16, with the lip 6 pressing the adjacent section of the strap tightly against the surface of the pipe, as 19. If the pipe is comparatively small in diameter, the plate 16 is engaged with a serration close to the collar, 70 but if larger, the plate is put into control of a serration farther from the collar. 75

The handle 1 is again turned until the strap is put under tension, and then the 80 handle is swung in a direction to maintain the nose or lip 6 in advance of the body of the strap. This causes the strap to tighten up on the piping until the grip becomes sufficient to force the pipe to turn with the handle. When the handle is moved in the opposite direction, the strap releases its hold 85 and permits either a return of the handle to its original position, or the removal of the strap and wrench from the piping. 90

What I claim is:

A pipe wrench comprising a threaded shank, a head turning upon its end, an internally threaded collar mounted on said shank, and a strap terminally attached to 95 said head and collar, said head having a rod rigidly projecting therefrom parallel with said shank, and said collar having an eye slideable on said rod.

In testimony that I claim the foregoing 100 invention, I have hereunto set my hand this 10th day of December, 1921.

GEORGE BRYAR.
